UNITED STATES PATENT OFFICE.

CLINTON D. HYRE, OF LEXINGTON, ILLINOIS, ASSIGNOR OF ONE-HALF TO
HARRISON L. HYRE, OF SAME PLACE.

EAVES-TROUGH HANGER.

SPECIFICATION forming part of Letters Patent No. 283,892, dated August 28, 1883.

Application filed May 10, 1883. (No model.)

To all whom it may concern:

Be it known that I, CLINTON D. HYRE, a citizen of the United States, residing at Lexington, in the county of McLean and State of Illinois, have invented certain new and useful Improvements in Eaves-Trough Hangers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to supporting devices for eaves troughs or gutters; and it consists of a combined eaves-trough hanger and brace composed of a single piece of wire, as herein-after more fully described.

20 In the annexed drawings, Figure 1 is a perspective view of an eaves-trough with my improved hanger in position for attachment to the roof or cornice of a building. Fig. 2 is a view of the hanger attached to a roof. Fig. 3 is a side view of the hanger, with dotted lines showing how it may be bent to adjust the trough up or down.

Like letters indicate like parts.

25 My eaves-trough hanger consists of the shank A, body or supporting portion B, lock C, and brace D, all of which are formed from a continuous piece of galvanized wire. The lock C is formed at one end with a hook, a, that engages the bend b at the junction of the body B and brace D, thus holding the trough E securely. At its opposite end the locking portion C is bent upward and merged in the shank A, which consists of doubled wire that is twisted or coiled sufficiently to insure strength and rigidity. This shank portion A of the hanger is formed at its upper end with an eye, c, Fig. 1, for passage of a nail or other fastening device by which the hanger is secured to

the roof, as shown in Fig. 2. The wire forming the shank portion of the hanger, after returning upon itself, is bent outward at a right angle, or nearly so, thus forming the upper portion, d, of the body or support B, a bend, e, being formed at its junction with the main portion of said body for the purpose of passing around or receiving the bead f of the eaves-trough. After passing beneath the eaves-trough and forming the main portion of the body B, the wire is bent outward at b to form the brace D, which terminates in an eye, g, 55 that is secured to the under side of the cornice, as shown in Fig. 2.

45 The shank A and brace D may be straight, or they may be bent at any desired angle to facilitate attachment to the roof or cornice of a building.

50 The device is easily adjusted for the purpose of raising or lowering the eaves-trough by changing the angles at which the shank and brace are bent, or by bending the portions 65 C and d up or down from a right angle with the shank, as shown by dotted lines in Fig. 3.

55 I am aware that eaves-trough hangers have heretofore been composed of wire bent into various shapes, the braces being formed in separate pieces; but I am not aware that an eaves-trough hanger with brace and lock formed from one piece of wire in the manner described has hitherto been known or used.

70 What I claim as my invention is—
75 An eaves-trough hanger consisting of the shank A, body B, brace D, and lock C, composed of one piece of wire bent into the form shown, substantially as described.

In testimony whereof I affix my signature in presence of two witnesses.

CLINTON D. HYRE.
